UNITED STATES PATENT OFFICE.

GLEN L. ARDERY, OF WOONSOCKET, SOUTH DAKOTA.

PHONOGRAPH STOP.

Application filed March 27, 1924. Serial No. 702,433.

To all whom it may concern:

Be it known that I, GLEN L. ARDERY, a citizen of the United States, residing at Woonsocket, in the county of Sanborn and State of South Dakota, have invented certain new and useful Improvements in a Phonograph Stop, of which the following is a specification.

This invention appertains to phonographs and the like and the primary object of the invention is to provide novel means for bringing about the stopping of the turntable of the phonograph, after the playing of the record.

Another prime object of the invention is the provision of novel means for returning the record arm toward the starting point of the record and into engagement with a brake trip, whereby the brake will be set for bringing about the stopping of the turntable.

A further prime object of the invention is the provision of novel means carried by the outer end of the tone arm including a lifting roller adapted to be preferably sprung into lowered position by a trip member carried by the record at the end of the groove therein for lifting the sound box above the surface of the record and for returning the tone arm back toward the edge of the record into engagement with the brake trip.

A further prime object of the invention is the provision of a novel brake carried by the phonograph and set in operation by the forcible engagement of the tone arm therewith.

A still further object of the invention is to provide a novel phonograph stop of the above character, which will be durable and efficient in use, one that will be simple and easy to manufacture and one which can be placed upon the market and incorporated with a phonograph at a minimum cost.

With these and other objects in view, the invention consists in the novel construction, arrangement and formation of parts, as will be hereinafter more specifically described, claimed and illustrated in the accompanying drawings, in which drawings:

Figure 1 is a plan view of a phonograph having the improved stop incorporated therewith.

Figure 2 is a fragmentary side elevation of the phonograph having the improved stop incorporated therewith.

Figure 3 is a fragmentary plan view of the phonograph with the turntable removed

showing the improved brake incorporated therewith.

Figure 4 is a fragmentary front elevation of a phonograph with the turntable in section showing the improved brake incorporated therewith, the brake being shown in edge elevation.

Figure 5 is a detail perspective view of the novel brake.

Figure 6 is a detail perspective view of the elevating means for the sound box, showing the latch carried thereby for permitting the forcible lowering of the roller and plunger when actuated by the trip associated with the record.

Figure 7 is a detail sectional view through the means for lifting the sound box and the stylus above the record and illustrating the pivoted actuating arm carried thereby for operating the brake, and

Figure 8 is a detail perspective view of the trip carried by the record.

Referring to the drawings in detail, wherein similar reference characters designate corresponding parts throughout the several views, the letter A generally indicates a phonograph of any standard construction and B the improved stop therefor.

As stated the phonograph A is of any preferred type and embodies the usual cabinet 10, the center pin 11 supporting the turntable 12, over which is adapted to travel the swinging tone arm 13. The tone arm 13 carries in the usual manner the sound box 14 having the ordinary holder 15, for the stylus 16. The turntable 12 includes the flat disk-shaped body plate 17 and the depending annular peripheral flange 18. The center pin 11 and the turntable 12 are adapted to receive phonograph records C, which in accordance with this invention have the inner sound groove 19 connected with an annular race groove 20 by means of a connecting way or groove 21. A radially extending slot 22 is also formed in each record adjacent to the aperture for receiving the center pin 11, for a purpose, which will be hereinafter more fully described.

The improved phonograph stop B comprises the tone arm carried lifting device and brake trip 25; the brake 45; and the record carrying trip 60 for the tone arm carrying lifting means and brake trip 25.

The tone arm carried lifting device and brake trip 25 comprises essentially a vertically disposed cylinder 26, which is provided

with a pivot lug 27 which is adjustably connected through the medium of a nut and bolt 28 with a clamp 29. This clamp 29 includes companion jaws 30 for engaging about the 5 stylus holder 15 whereby the cylinder can be held in an operative position relative to the sound box and phonograph record C. Slidably mounted within the cylinder 26 is a plunger 31 rotatably carrying at its lower 10 end a friction wheel 32, the purpose of which will be hereinafter more fully described. The plunger 31 carries at diametrically opposite points outwardly extending guide pins 33 which are mounted in guide slots 15 34 formed in the cylinder. The upper ends of the guide slots 34 terminate in notches 35 making a substantially bayonet slot arrangement. An expansion spring 36 is arranged within the cylinder and normally 20 urges the plunger downward so as to bring the roller 32 into frictional contact with the record and to raise the sound box 14, so that the stylus 16 will be lifted out of the sound groove and above the record. It can be seen 25 that by pushing in on the plunger and turning the same so as to move the lug 33 in the notches 35 that the friction roller or wheel 32 can be held in a raised position above the lower end of the needle or stylus. When the 30 wheel or friction roller 32 is moved to its operative record engaging position, the same is disposed at an angle to the circumference of the record, whereby the tone arm will be moved toward the periphery of the record 35 due to the rotation thereof. A pivoted latch 37 is connected by means of a pivot pin 38 to a suitable lug 39 carried by the cylinder 26 and the upper end of this lever is enlarged and notched to provide a head 40 for engaging one pin 33 when the pins are positioned in the notches 35. This trip lever 40 45 is adapted to be actuated by the record carried trip 60, when the tone arm is moved over the race groove 20. It can be seen that 50 when the lower end of the trip lever 37 is hit by the record carried trip 60, that the same will be rocked on its pivot pin 38 thus bringing the head 40 into engagement with one pin 33 and thereby moving the pins out 55 of the notches 35 allowing the spring in the cylinder to forcibly move the plunger below the stylus or needle. Extending at right angles to the lugs 39 is a horizontally disposed pivot bracket 41 which has connected 60 thereto by means of a pivot pin 42 an arm 43. This arm is formed relatively long and its outer end is provided with a right angularly disposed upstanding foot 44 which is adapted to operate the brake 45 when the tone arm is swung to the outer edge of the bracket. This arm 43 can be swung to a raised position, when the automatic stop is not in use.

The brake 45 comprises a base plate 46 65 which is secured in any preferred way to the

top plate of the phonograph cabinet 10 below the turntable 12 and adjacent to the periphery thereof. This base plate 46 supports aligned guides 47 which slidably receive the radial movable brake arm 48. The forward end of this brake arm 48 is provided with a manipulating handle 49 to permit the setting thereof, as will become hereinafter more fully apparent. The sliding brake arm 48 is provided at a point intermediate its ends with a suitable brake shoe 50 which is carried by a brake shoe holder 51 secured to the upper surface of the brake arm. A leaf spring 52 is carried by the base plate 46 and engages the holder 51 for normally urging the brake arm outwardly and the shoe 50 into forcible engagement with the inner surface of the peripheral flange 18 of the turntable 12. The inner end of the brake arm 48 is provided with an upstanding trip lug 53, for a purpose, which will be hereinafter more fully described. The rear guide bracket 47 carries a pivot pin or shaft 54 on which is rockably mounted adjacent to its inner end the brake trip lever 55. The extreme inner end of the brake trip lever 55 is provided with a right-angularly extending arm 56 and it can be seen that by pushing in on the manipulating handle 49, that the brake arm 48 can be moved back against the tension of the leaf spring 52 to position the lug 53 in rear of the arm 56 of the pivoted brake trip lever 55. When the arm 56 of the brake trip lever 55 is disposed in the path of the lug 53 outward movement of the brake arm 48 is prevented. The outer end of the brake lever 55 is provided with an upstanding extension 57 which carries an L-shaped operating arm 58, which is adapted to be engaged by the pivoted arm 43 carried by the tone arm lifting device and brake trip 25.

The record carried trip 60 embodies a longitudinally extending body 61, which is adapted to extend radially from the center of the record C toward the race groove 20. The inner end of the body 61 is provided with a laterally extending L-shaped lug 62 which is adapted to be inserted in the slot 22 formed in the record C and the placing of this L-shaped lug within the slot holds the record carried trip in place. The outer end of the body 61 is provided with an upstanding lug 63 which terminates directly at the race groove 20.

In operation of the improved device, the plunger 31 is pushed upwardly and turned to force the pins in the notches 35 and the arm 43 is swung to its lowered horizontal position. The record is now played in the ordinary manner. Prior to the playing of the record the arm 48 is pushed inwardly as heretofore described, as clearly shown in Figures 3 and 5 of the drawings. Now when the stylus reaches the innermost sound groove the same will follow the groove 21

- and ride into the race groove 20. This will carry the trip lever 37 in the path of the lug 63, which will operate the same in such a manner as to push the head 40 thereof into engagement with one pin 33 thus moving the pins from out of engagement with the lower walls of the notches and permitting the expansion spring to forcibly lower the plunger below the level of the stylus. The 5 friction roller 32 which can be padded if so desired, engages the upper surface of the record at an angle, as heretofore stated and effectively lifts the stylus 16 above the record and out of the sound groove. The tone 10 arm will now be moved outward toward the periphery of the record and the foot 44 will be moved into engagement with the L-shaped lug 58 formed on the brake trip lever 55. This will rock the brake trip lever 55 and 15 move the arm 56 thereof above and out of the path of the lug 53 carried by the brake arm 48. This will permit the sliding of the brake arm 48 under the influence of the spring 52 which will forcibly move the 20 shoe 50 into contact with the peripheral flanges 18 of the turntable 12 and bring about the stopping thereof. In view of the fact that the lug 44 of the arm 43 is positioned a relative great distance in advance 25 of the roller 32, the turntable will be brought to a stop, before the roller rides off of the turntable, which prevents injury to any of the parts of the phonograph and record.
- When a new record is to be played, the 30 parts of the stop are reset as heretofore described.
- Changes in details may be made without departing from the spirit or the scope of this invention.
- 40 What I claim as new is:
1. The combination with a phonograph including a cabinet, a turntable, a swinging tone arm, and a sound box, and a record on the turntable, of a stop for the phonograph including a brake for engaging the turntable, a trip lever associated with the brake for normally holding the same from out of engagement with the turntable, means carried by the tone arm for lifting the tone 45 arm above the record and toward the brake trip, means carried by the tone arm lifting means for actuating the brake trip, when the tone arm is moved toward the brake trip, means normally holding said tone arm lifting means in an inoperative position, and means disposed adjacent to the inner sound groove of the record for operating said last mentioned means to permit the raising of the tone arm.
  2. The combination with a phonograph including a cabinet, a swinging tone arm, a sound box, a turntable, and a record upon the turntable, of an automatic stop for the turntable including a brake arranged to engage the turntable, a pivoted trip lever for 50 normally holding the brake in an inoperative position, an operating arm formed on the trip lever arranged to extend above the upper surface of the record, a sliding plunger associated with the sound box, a friction roller carried by the lower end of the plunger, a pivoted trip lever for causing the plunger to be moved to its lowered operative position for forcing the roller into engagement with the record and the sound box 55 to a raised position, and a record carried trip disposed adjacent to the inner sound groove of the record for operating said trip lever.
3. In combination with a phonograph including a cabinet, a turntable, a swinging tone arm, a sound box, a record upon the turntable, of an automatic stop for the turntable including a brake carried by the cabinet for the turntable, a pivoted trip lever associated with the brake for normally holding the same in an inoperative position, an operating arm disposed on the outer end of the brake lever disposed above the upper surface of the record, a vertically disposed cylinder, means clamping the cylinder to the sound box, a sliding plunger mounted in the cylinder, a friction roller carried by the lower end of the plunger, resilient means normally urging the plunger to a lowered position and the roller in contact with the record for raising the sound box, a pivoted trip lever carried by the cylinder for permitting the plunger to be moved to its lowered position, a trip carried by the record and disposed adjacent to the inner sound groove for engaging and operating said trip lever to cause the lowering of said plunger, whereby the friction roller will cause the outward swinging movement of the tone arm and the raising of the sound box, and a pivoted arm carried by said plunger for engaging the operating arm on said brake trip lever.
4. The combination with a phonograph having a cabinet, a turntable, a swinging tone arm, a pivoted sound box, a stylus holder, a stylus in said holder and a record disposed upon the turntable, of means for bringing about the stopping of the turntable upon the playing of the record including a brake carried by the cabinet and disposed beneath the turntable for normally engaging the turntable, a pivoted trip lever for normally holding the brake out of engagement with the turntable, an upstanding arm carried by the trip lever disposed above the upper surface of the record, a cylinder, a clamp carried by the cylinder for engaging the stylus holder, and a sliding plunger in the cylinder, a friction roller disposed at an angle to the circumference of the record carried by the plunger, resilient means normally urging the plunger to a lowered position for moving the roller

into engagement with the record and the lifting of the sound box, the roller being adapted to move the tone arm toward the outer end of the record, when the same is in engagement with the record, means for normally holding the plunger and roller in a raised position including a pin and a notch, and a pivoted bell crank lever carried by the cylinder arranged to move the 10 pin out of the notch for permitting the lowering of the plunger, a trip carried by the record and disposed adjacent to the inner sound groove thereof for operating said pivoted bell crank lever, and a pivoted arm carried by the cylinder for engaging the operating arm on the brake trip lever.

5. The combination with a phonograph including a cabinet, a turntable, a swinging tone arm, a sound box, a record upon the turntable having the usual sound groove therein and provided with an annular race groove inward of the sound groove, a communicating lead groove, of an automatic stop for the turntable including a sliding 25 plunger carried by the sound box, a roller mounted by the lower end of the plunger, means normally holding the plunger in a raised position and the roller above said

record, and a pivoted bell crank lever for causing the lowering of the plunger upon the actuation thereof, a brake carried by the casing and disposed below the turntable for normally engaging the same, and a pivoted 30 brake trip lever normally holding the brake from out of engagement with the turntable 35 and including an arm arranged above the record, a pivoted trip arm carried by the sound box and arranged to engage the arm on the brake trip lever when the tone arm is moved toward the outer edge of the record, 40 and a record carried trip for actuating the bell crank lever including a body arranged radially on the record and extending from the axial center thereof to the race groove, 45 means for holding the body on the record, the outer end of the body having an upstanding lug disposed adjacent to the race groove for engaging said bell crank lever when the stylus of the sound box moves into the race groove. 50

In testimony whereof I affix my signature in presence of two witnesses.

GLEN L. ARDERY.
